UNITED STATES PATENT OFFICE.

CLIFFORD D. BABCOCK, OF NEW YORK, N. Y., ASSIGNOR TO UNITED WIRELESS TELEGRAPH COMPANY, OF NEW YORK, N. Y., A CORPORATION OF MAINE.

WAVE-RESPONSIVE DEVICE.

No. 901,942.

Specification of Letters Patent.

Patented Oct. 27, 1908.

Application filed August 27, 1906. Serial No. 332,196.

To all whom it may concern:

Be it known that I, CLIFFORD D. BABCOCK, a citizen of the United States, residing at New York, in the county of New York and State of New York, have invented a new and useful Wave-Responsive Device, of which the following is a specification.

This invention relates to improvements in mechanism for wave responsive or detecting devices to be used in the receiving apparatus of a wireless telegraph system, and the object is to obtain a simple and cheap device in which to employ well known materials as the sensitive substances.

The invention will be best understood from a description of one particular embodiment thereof which is illustrated in the accompanying drawing in which

Figure 1 is a view in side elevation of my improved receiving device, and Fig. 2 is a vertical sectional view of the parts disassembled to show clearly the relative arrangement thereof.

This invention contemplates the use of a concrete mass or body of crystals or a single crystal of carborundum or other crystalline material as the wave responsive or detecting device. Such substances possess very high specific internal resistance and high negative temperature coefficient or high positive conductivity coefficient, so that the conductivity increases sufficiently rapidly under the heating influence of Hertz oscillations to obtain a valve or trigger effect to release the energy of an auxiliary source of electromotive force to operate a telephone receiver. This is a well-known electrical property of this substance, which has been used as a motor starter. I therefore utilize this characteristic by inserting a mass or single crystal of such substance in the local or indicating circuit of the receiving apparatus containing also the requisite auxiliary source of electromotive force and potentiometer for regulating the same, whereby upon receipt of the Hertz waves and passage of the oscillations caused thereby through the crystalline material, a flow of current from the auxiliary source takes place in said local circuit which may be detected by any suitable form of indicating instrument, such as a telephone receiver. The detector should be connected in the usual way across the terminals of the indicating device.

In the embodiment of my invention shown in the drawing, the device comprises a metallic base plate C upon which is mounted an insulating standard I secured thereto by a screw V. Mounted upon said standard by means of a screw T' is a spring contact arm S, between which and an adjustable contact b also mounted upon the base plate C, the carborundum X or other sensitive material is held, said contact b being provided with a knurled adjusting head B.

In order to adjust the pressure of the spring contact arm S upon the sensitive element X, I provide an adjusting screw P mounted in an arm A which is secured upon the standard I and above the arm S, also by the screw T', a set nut N being provided to hold the parts firmly in position.

In inserting the crystalline mass between the spring arm S and the contact b, the latter is adjusted until said mass will just slip easily in between the two when the spring is in normal position or not under pressure from the screw P. Said screw is then adjusted to bring the spring S down upon the crystal and hold it at the desired pressure between itself and the contact b. By means of this construction a light but firm and adjustable contact may be maintained upon the sensitive element X without danger of crushing the crystalline structure thereof and by reason of the adjustability of contact b the spring arm S need be deflected but to a slight degree in making contact with the sensitive element whereby the spring is always maintained at its condition of great resiliency, thus permitting any degree of light pressure on said member. This feature is very desirable as for greatest efficiency of the device it is necessary that the area of contact with the sensitive member be as small as possible consistent with the firm holding thereof between the parts S and b.

For connection of the device in circuit, a binding nut B' is provided on the screw T, the other connection being effected by the screw which secures the device to its support, for the reception of which screw a recess L is provided in the rear end of the base plate C.

The crystalline substances used with this device should in use be carefully shielded or protected from the effects of atmospheric changes of temperature and humidity, as by

inclosure in a moisture-proof or heat-insulating receptacle, and by the inclusion in the receptacle of a moisture-absorbing material. Before using a given crystal, or body or mass of crystals, it should be carefully tested to insure its operativeness, as many samples are inoperative, owing probably to a crystalline formation not adapted to utilize the resistance-varying properties of a crystal. A single detached crystal usually gives better results than a mass or body of crystals. The best operation is obtained by placing the edges, and not the surfaces, which are insulating in character, of a single crystal in contact with the spring S and contact b in order to obtain a small area of contact with a single crystal so as to obtain a maximum effect of the heating by the oscillations and a resulting greater abrupt change in the variation of the internal resistance of the crystalline substance. The surfaces of the crystals are apparently chemically and physically different from the edges, and so are non-conducting. A loose contact in the circuit of any part of the crystal does not give good results, and for this reason the spring S is an important feature as it insures a sufficient action of the oscillatory current to operatively vary the resistance of the crystal.

This detector owes its efficiency to the high temperature coefficient of the substance used and the small size of the effective contact which limits the active portion of the substance to a very small volume. In a commercially sensitive detector the operative portion of the carborundum is a minute pyramidal mass, about a thousandth of an inch on an edge, and containing about a billionth of a cubic inch of the substance. The effective area of contact with the circuit is also very small, being of the order of a few millionths of a square inch.

The importance of using a potentiometer to quite accurately regulate the electromotive force of the auxiliary source is shown by the fact that the curve of conductivity of the device is flat at zero up to a difference of potential of about one-half a volt across its terminals, when the curve rises rapidly, its steepest rise being between one volt and one and one-tenth volts, where for an increase of potential of ten per cent., the conductivity increases more than one hundred per cent. At a potential difference greater than one and one-tenth volts, the rise in conductivity is decreased rapidly. It has been demonstrated in practice that with carborundum, the maximum response in the telephone from a distant station is between one and one and two-tenths volts. From these facts it is obvious and is hereby recommended that to obtain practical results, a battery should be used in order to obtain an operative condition of conductivity of the substance which cannot be had without a potential difference

of at least more than half a volt; and that a potentiometer should be used in order to constantly maintain under varying conditions, a potential difference across the terminals of the device of between one and one and two tenths volts.

When during use, a given mass becomes inoperative, this device offers a ready means of replacement by a new operative mass or crystal.

It is always necessary in practice to connect this device in series with an auxiliary source of electromotive force such as a primary battery, because none of the energy of the received oscillations is translated into a current suitable for operating the indicating device, and so a battery is necessary to operate said device by the abrupt change in the electromotive force of the battery circuit caused by the variation of the internal resistance of the mass of material due to the action of the received oscillations.

It has proved to be impossible in practice to use the device without a battery or other suitable source of electromotive force. A potentiometer should also be used to regulate the battery action. In other respects the device may be used in the circuits of wireless telegraphy apparatus as well known to those skilled in the art.

I claim:

1. A wave responsive device, which comprises a metal base, means for connecting the base to one side of the electric circuit, an adjustable contact mounted on the base as a support for a sensitive substance, a spring contact arm having a free end operatively positioned opposite said contact support to bear lightly on such substance, an insulating standard mounted on said metal base as a support for the other end of the spring contact arm, adjustable means bearing on the spring contact arm intermediate its ends to press it firmly against the sensitive substance, a support for said adjustable means and mounted on said standard, and means for connecting said spring contact arm to the other side of the circuit.

2. A wave responsive device, which comprises a contact support for a sensitive substance, a spring contact arm having a free end operatively positioned opposite said contact to bear lightly on such substance, a support for the other end of the spring contact, adjustable means intermediate the free and supported ends of the spring contact arm to press the free end firmly against the sensitive substance, and a support for said adjustable means.

3. A wave responsive device which comprises an adjustable contact, a spring contact arm having a free end operatively positioned opposite said adjustable contact, a support for the other end of the spring contact, means intermediate the free and supported ends of

the spring contact arm to adjust it with respect to the adjustable contact, and a support for said adjusting means.

4. A wave responsive device which comprises a metal base, an adjustable contact mounted thereon, an insulating standard also mounted thereon, a spring contact supported on the insulating standard and operatively positioned opposite said adjustable contact, an adjusting screw bearing on said spring contact intermediate the point of support and the operatively positioned part of the spring contact, a supporting arm for the adjusting screw mounted above the contact spring on the insulating standard, means for holding together in position the insulating standard, the contact spring, and the supporting arm, means for connecting the spring-supporting arm to one terminal of the circuit, and means for connecting the metal base to the other terminal of the circuit.

5. A wave responsive device, which comprises a base, a contact mounted therein, a standard mounted on the base, a spring contact arm mounted on said standard so that one end of the arm is operatively positioned with respect to said contact, an adjusting screw bearing on the spring contact arm between its point of support and its operative end, and a support for the adjusting screw also carried by said standard.

6. A wave responsive device, which comprises a contact, a spring contact arm one end of which is operatively positioned with respect to said contact, a support for the spring contact, adjusting means acting on the spring contact between its point of support and its operative end, and a support for the adjusting means.

7. A wave responsive device which comprises a conducting base, an adjustable contact mounted thereon, an insulating stand-

ard mounted on the base, a spring contact mounted on said insulating standard and operatively positioned with respect to said adjustable contact, an adjusting screw bearing on said spring contact, and a support for said screw.

8. A wave responsive device which comprises a metal base, means for connecting the base to one side of the electric circuit, an adjustable contact mounted on the base as a support for a sensitive substance, a spring contact arm having a free end operatively positioned opposite said adjustable contact to bear lightly on such substance, an insulating standard mounted on said metal base as a support for the other end of the spring contact arm, said standard having opposing threaded openings separated by an integral insulating barrier, a screw entering one of said openings to secure the standard to the metal base, an adjusting screw bearing on the spring contact arm intermediate its ends to press it firmly as well as lightly against the sensitive substance, a supporting arm for the adjusting screw and mounted above the end of the spring contact arm which is secured to the standard, a screw entering the second opening in the insulating standard to hold the spring contact arm and its supporting arm to the insulating standard, a set nut on said screw for securing together the standard, spring contact arm and its supporting arm, and a binding nut on the same screw as the set nut and above the set nut to secure the circuit lead of the other side of the circuit.

In testimony whereof I affix my signature in the presence of two witnesses.

CLIFFORD D. BABCOCK.
